UNITED STATES PATENT OFFICE.

JOSEPH OVILA FORTIN, OF OTTAWA, ONTARIO, CANADA.

CAMPING OUTFIT.

Application filed February 2, 1925. Serial No. 6,456.

This invention relates to collapsible camping outfits and the object of this invention is to provide sleeping quarters for campers, which will occupy small space when in a folded or collapsed condition and which may be erected in a minimum of time by one person, even during a wind or rain storm.

It is a further object of the invention to provide a combined tent and bed, which will resist severe weather conditions, without the use of the usual long rigid supporting members and which may be conveniently used in connection with motor travel.

Further objects of the invention will be apparent from the detail description now to be given in connection with the accompanying drawings in which:

20 Figure 1 is a rear perspective view of the camping outfit set up,

Figure 2 is a perspective view showing the various parts in erected position,

25 Figure 3 is a perspective view of the bed canvas in an inverted position, and

Figure 4 is an elevation showing the construction of the legs for the bed.

Figure 5 is an elevation, partly in section, of a tent supporting strut.

30 Generally stated the invention consists of a tent and bed connected and supported by tension and compression members, all of which are connected to the tent and bed and are adapted to be folded with the bed, bed clothes, floor-mat, etc. and tent into a small cylindrical parcel.

In Figures 1 and 2 the outfit is shown in erected position between a tree and a motor car. The member 1, which may be a chain or rope, is permanently secured at one end to a ring 2 and at the other end to, preferably, a spring lock 3 adapted to engage the ring 2. To the ring 2 are fastened two main tension members 4, which pass through small holes in the tent at the points 17 and extend beyond the other end of the tent, where they are secured to a ring 5. Two struts 6 are connected to the tension members as shown, the distance between the struts being approximately equal to the length of the bed. By means of the sleeves 8, a sheet of canvas 7 forming the bed is held on the members 4 between the struts 6, the canvas 7 being widest at its ends.

At points on the members 4, equivalent

to the four corners of the bed plane, are located four telescopic legs or jacks 9. A suitable and convenient form of leg, shown in Figure 4 consists of a threaded rod 10, 60 a recessed lug 10^a through which the pin 11 passes to hold the leg attached to the member 4, and a nut 12 engaging the thread on the rod 10 and adapted to rest on a piece of tubing 13, the inside diameter of which 65 clears the thread on the rod. The tubing 13 is split or spread at its lower end to adapt it to rest on the ground and if desired on the edges of the tent to obviate the necessity of using pegs. 70

The members 14, which pass through the curved sleeves 15 sewed on the under side of the bed canvas 7, are provided with adjustable swivel joints 16 and are connected at each end to the tension mem- 75 bers 4.

The roof of the tent is held up by means of the telescopic members 23, suitably engaging the tension member 24, one end of which is adapted to be secured to, say, the 80 steering wheel of a motor car, and the other end to a peg 25 which is located diagonally to the position of the tent. The adjustment of the members 23 is effected by rotation of a nut 12 in a manner similar to 85 that of the legs of the bed as will be clear without further description. The lower ends of the members 23 are secured to the tension members 4 at points at or near the inner corners of the bed. Lugs 26 may be 90 provided on the rear of the tent, to which additional securing means 27 may be attached and the front flap may be left loose or secured in any desired manner.

The tent is so constructed as to give an 95 inwardly curved portion in the ridge 19 and edge of the end walls indicated by 18. The bed canvas is cut in like manner. This arrangement is provided to make it possible to readily secure a tight un wrinkled 100 roof and bed canvas. Moreover it should be stated that a still further object of this construction is to secure the benefit of the gripping tendency of the canvas on the tension members. An analysis of the va- 105 rious stresses exerted in the canvas of the bed by a normal load will clearly indicate the value of and benefits derived from this arrangement of the canvas.

To erect the camping outfit the member 1 110 is fastened to a suitable tree or other fixed point, the ring 5 is hitched to a motor car

or other source of power to exert a pull on the tension members 4 which are thus raised to a substantially horizontal position, the struts 6 causing the said members, carrying the bed canvas to arrange themselves in the form of two triangles and a quadrangle as shown. It will be noted that the portions of the members 4 in contact with the bed canvas do not lie in straight lines, as do the remaining portions, owing to the particular cut of the canvas above described. This produces a tension crosswise in the canvas, which increases with the pull at 5. The legs 9 are then set in position, the first one being placed at the corner where the ground is highest. The height of the legs is suitably adjusted by means of the nuts 12 and the tension exerted in the members 4 holds the legs securely in place, causing the plane of the bed to be higher than the points at 2 and 5.

One end of the rope 24 is secured to the car and the telescopic members 23 are now raised into position by a pull on the free end 25 of the rope 24, which end is then fastened by means, such as the peg 25. The wall opposite the bed or the front hangs from the ridge 19 and thus forms the fly of the tent.

It will be observed that when folding and 30 rolling up the camping outfit the edge 20 is fixed, the portions 18 drop on the bed, when the ridge support is disengaged, and the ridge 19 may be thrown over the bed parallel with the edge 20, while the fly 21 follows, 35 the lower edge 22 being placed on and parallel with the ridge 19 and edge 20. The supports 23 and legs 9 lay across the bed parallel with the struts 6. When the structure is in this position the ring 5 is released 40 and with the foreparts of the members 4 are thrown over the bed and folded tent. The strut 6 is seized and used to control the rolling up operation. The members 1, 2 and 3 are used to encircle the bundle and they are 45 thus first available for again pitching camp. A waterproof sheet, which may serve as a ground mat, is then wrapped around the cylindrical bundle thus formed. This small bundle may be readily carried on the running 50 board of a motor car.

It is to be noted that all the parts of the complete outfit are interconnected so that none may be lost in moving, the bed and bedding are not exposed to the weather, all 55 the joints are universal and all the parts of the bed are interchangeable and adjustable. The swivel joint 16 makes it possible to take care of shrinkage or expansion of the bed canvas in changeable weather similarly 60 the supports 23 may be adjusted to suit particular requirements. With this camping outfit one person can readily set up camp in a minimum of time, even during a wind or rain storm.

65 The many advantages to be derived from

the construction herein described will be obvious and it is to be understood that many changes may be made therein without departing from the scope of the invention as defined in the following claims.

70

What I claim is:—

1. A camping outfit adapted for simultaneous erection comprising in combination a tent, a fabric sheet adapted to form a bed within the tent, flexible tension members extending along the longitudinal edges of said sheet and through opposite walls of the tent, struts loosely connected to said tension members for spreading the same apart so that when said members are under tension said struts are under compression, and vertically adjustable means loosely connected to the tension members for maintaining the sheet supported above the ground when the ends of said members are anchored at or near the ground, the connections between the several members being permanent but loose or flexible so that the complete outfit moves as a unit and is compact when folded.

80

85

90

95

2. A camping outfit as defined in claim 1 wherein the longitudinal edges of said fabric sheet are inwardly curved so that the sheet is under lateral tension throughout substantially its entire length when said tension members are under tension.

3. A camping outfit as defined in claim 1 wherein the longitudinal edges of said fabric sheet are inwardly curved and tubular, the flexible tension members being within said tubular edges and having a tension member extending along the ridge of said tent and out through holes in the tent at either end to anchoring points, the ridge of the tent being downwardly curved so that the tension applied to the ridge tension member maintains the sloping wall or roof of the tent substantially uniformly taut throughout and adjustable members loosely connected at one end to one of the tension members adjacent each end of the sheet member and at their other ends adapted to engage said ridge tension member.

100

105

110

115

4. A camping outfit adapted for simultaneous erection, comprising in combination a tent, a fabric sheet adapted to form a bed within the tent and having inwardly curved longitudinal edges, flexible tension members engaging said longitudinal edges, means for securing the tension members to anchoring points outside the tent, struts adjacent each end of the sheet member and loosely connected to said tension members for spreading the same apart, adjustable vertical legs loosely engaging the tension members adjacent all corners of the sheet member, a tension member extending along the ridge of said tent and adjustable members loosely engaging said ridge tension member and adapted to be supported at corners of said bed and hold the ridge of the tent in erected position

120

125

130

when said ridge tension member is anchored at points at or near the ground, all of said elements being so connected that the outfit moves as a unit and may be rolled into a compact cylindrical form.

5. A camping outfit adapted to move as a unit for simultaneous erection comprising in combination a tent, a sheet member adapted to form a bed within the tent, the 10 longitudinal edges of said sheet member being inwardly curved and tubular, main flexible tension members within said tubular edges and passing out through holes in the tent at each end thereof and extending to 15 anchoring points, curved sleeves on the under side of the sheet member adjacent each end thereof and adjustable flexible tension members passing through said sleeves and secured at their ends to the said main tension members.

6. A camping outfit adapted to move as a unit for simultaneous erection which when erected comprises a tent having a single roof panel rearwardly and downwardly inclined, a vertical rear panel depending from the lower edge of said roof panel and vertical side panels connected to said roof and rear panels, a downwardly curved ridge for said tent, a flexible tension member lying in and along said curved ridge and extending through holes in the side panels adjacent the uppermost extremities thereof and being of sufficient length to extend to anchoring points disposed forwardly and laterally of said ridge, a fabric sheet to form a bed having tubular, inwardly curved longitudinal edges, flexible tension members extending through said tubular edges and passing out through holes in the side panels and extending at each end to a common anchoring point in line with the longitudinal centre line of the bed, vertical adjustable feet loose-

ly connected to the tension members of the bed adjacent each corner thereof so as to support the bed at substantially the level 45 of the bottom of the roof panel, adjustable sectional struts loosely connected to the forward tension member of the bed adjacent each end thereof, said struts being inclined forwardly and upwardly and loosely engageable with the tension member of the ridge, a third flexible tension member connected at its ends to spaced points on the line of juncture of the roof and rear panels and extending to an anchoring point at the 55 rear of the tent, but above the plane of the roof panel and horizontal bars of greater length than the width of the bed and adapted to space the tension members of the bed apart at the ends of the bed. 60

7. A camping outfit comprising in combination a tent, a bed sheet in the tent, flexible tension members extending along the ridge of the tent and the longitudinal edges of the bed sheet, struts to spread the bed 65 sheet tension members apart adjacent the ends of the bed, leg members carried by the bed sheet tension members adjacent the corners of said sheet and axially adjustable members adapted to extend between one of 70 the bed sheet tension members and the tent ridge, all said elements being so interconnected as to be portable as a unitary structure and capable, after preliminary positioning of the parts, of simultaneous erection 75 by an individual person solely by the action of tensioning said tension members, and capable of being maintained in erect position merely by anchoring the ends of said tension members to points outside the 80 tent.

In testimony whereof I affix my signature.

JOSEPH OVILA FORTIN.
